UNITED STATES PATENT OFFICE

2,607,326

COMBUSTION CHAMBER FOR DIESEL ENGINES

Emil Grieshaber, Milwaukee, Wis., assignor to
Nordberg Manufacturing Company, Milwaukee,
Wis., a corporation of Wisconsin

Application October 18, 1949, Serial No. 122,033

3 Claims. (Cl. 123—32)

1

My invention relates to improvements in combustion chambers for internal combustion engines and has for one purpose to provide a combustion chamber wherein rotary turbulence or mixing movement is provided.

Another purpose is to provide a combustion chamber associated with a power cell.

Another purpose is to provide a combustion chamber in which the fuel is initially delivered into a sub-chamber in the cylinder head, in an optimum relation to an energy cell.

Other purposes will appear from time to time in the course of the specification and claims.

My invention is illustrated more or less diagrammatically in the accompanying drawings, wherein:

Figure 1 is a vertical section through the cylinder head; and

Figure 2 is a section on the lines 2—2 of Figure 1.

Like parts are indicated by like symbols throughout the specification and drawings.

I have shown only the head of the engine, the details of the cylinder itself not forming part of the present invention.

Referring to the drawings, 1 is any suitable cylinder or cylinder liner, the details of which do not of themselves form part of the present invention. The piston is omitted, but it will be understood that any suitable piston may be employed, movable within the cylinder liner 1.

2 generally indicates a cylinder head suitably secured to or held in relation to the cylinder by bolts, or other suitable means, not herein shown. Any suitable water jacket spaces 3 may be employed. 4 indicates the air intake passage, any suitable gas exhaust passage being provided in the cylinder head, but not shown in the accompanying drawings. The passages terminate in or communicate with the combustion chamber 5, ingress and egress being controlled by any suitable valves, such as the valve indicated at 6, with its stem 6a mounted for reciprocation in any suitable sleeve 7 and normally urged toward closed position by any suitable spring 8, compressed between abutments 9 and 10.

Liquid fuel is admitted to the chamber 5 by any suitable injection nozzle assembly 12, the details of which do not of themselves form part of the present invention. It will be understood, however, that the fuel is injected through the inlet passage 13, aligned with the energy cell assembly, generally indicated at A. This assembly includes a sleeve 14, having the generally

conic inlet 15, terminating in a throat 16, which, in turn, communicates with the conically expanded wall portion 17. 18 indicates the cell proper, with its converging walled entry passage 19, aligned with the neck 16 and aligned generally with the path of delivery of the fuel through the inlet duct 13.

The cylinder head chamber 5 is shown in some detail in Figure 2. In considering the relation of the wall to the energy cell assembly A, the wall portions 5a and 5b converge toward the conic passage 15, the wall 5a lying in a plane generally parallel with the direction of delivery of the fuel, the wall 5b being divergently inclined or curved therefrom. The intermediate wall portion of the chamber 5, between the divergent ends of the portions 5a and 5b, forms a sequence of lobes 5c, 5d and 5e, separated by inward projections 5f and 5g.

The general direction of travel of the fuel or mixture from the energy cell is indicated by arrows. These may be taken as diagrammatic and as indicating generally the type of turbulence which is produced. It will be understood that a uni-directional jet of fuel is delivered from the inlet valve 12 toward and into the power cell of the energy cell unit through the neck 16. The return flow from the energy cell fans out through the chamber 5 and turbulence takes place generally as shown by the arrows of Figure 2. It will be understood that ignition takes place when the top of the piston, as shown, closes or practically closes the bottom of the chamber 5. It will be noted that the chamber 5 is off-center in relation to the cylinder bore, the contour of the bore being indicated in dotted line in Figure 2.

It will be realized that whereas I have described and shown a practical and operative device, nevertheless many changes may be made in size, shape, number and disposition of parts without departing from the spirit of my invention. I therefore wish my description and drawings to be taken as in a broad sense illustrative or diagrammatic, rather than as limiting me to my specific showing herein. For example, the contour, size and number of the lobes 5c, 5d and 5e may be varied. I find it advantageous, however, that the fuel injecting valve 12 delivers fuel in general parallelism with a generally rectilinear wall member 5a and that the resultant delivery from the energy cell diverges throughout the chamber 5, and includes delivery to the various lobes provided, to the end that

there may be substantial rotary turbulence localized at the various lobes.

I claim:

1. In an injection type engine having a cylinder and a piston in the cylinder, a cylinder head defining with the cylinder and piston a combustion space, a recess in said cylinder head, of a diameter less than the diameter of the cylinder, said recess being open to the interior of the cylinder, a closed-ended cell having a restricted opening in communication with the interior of said recess, and a liquid fuel admitting nozzle formed and adapted to deliver liquid fuel into the recess along an axis in general alignment with the axis of the opening of said cell, the axis of delivery of said nozzle being substantially offset from the center of said recess, the side wall of said recess facing the cell opening having a plurality of inwardly projecting portions defining a series of adjacent lobes arranged side by side in said side wall of said recess, said nozzle being disposed to discharge fuel through an end lobe of said series toward

said cell opening, the remaining lobes being laterally offset from the generally common axis of the nozzle and the cell opening.

- 5 2. The structure of claim 1 characterized in
that the lobes are generally equi-distant from
the cell opening.

10 3. The structure of claim 1 characterized in
that said lobes are proportioned and adapted
to receive generally similar proportions of the
spray from the cell.

EMIL GRIESHABER.
